UNITED STATES PATENT OFFICE

2,432,284

CREEL

Charles Chipman, Easton, Pa., assignor to Hattuck Silk Throwing Company, Easton, Pa., a corporation of Pennsylvania

Application October 14, 1943, Serial No. 506,130

3 Claims. (Cl. 242—131)

1

This invention relates to spinning machines, and has reference more particularly to ring spinning machines of the type known as "down" spinners in which the threads to be spun or twisted are drawn from supply packages at a high level and the twisted yarn wound upon spools or bobbins at a lower level.

In the preparation of rayon and other multi-filament synthetic threads for knitting or weaving purposes it has been necessary and generally customary heretofore to first skein the threads from the relatively large supply packages received from the thread manufacturer, then to reel the threads from the skeins, and finally to spin (twist) the threads incident to drawing them from the reels and winding them onto spools or bobbins. This preparation is not only costly from the standpoint of labor entailed and the time consumed, but also by reason of requiring several different machines to carry out the various steps of the process.

My invention has for its chief aim the simplification of the above procedure and the obviation of its various drawbacks, or, in other words, to enable conversion of multiple filament threads of the kind referred to into yarns of a definite twist in a single continuous operation.

This objective I realize in practice as herein-after more fully disclosed, through provision of a structurally refined twisting machine characterized by having improved rack means whereon the relatively large original thread packages are accommodated for ready removal of the threads without danger of interference with each other notwithstanding close spacing of the spindles for the spools or bobbins onto which the finished yarns are wound.

Other objects and attendant advantages will appear from the following detailed description of the attached drawings, wherein

Fig. 1 is a broken-out view in side elevation of my improved spinning machine.

Fig. 2 shows the machine in top plan.

Fig. 3 shows the elevation of the left hand end of the machine as considered in Fig. 1.

Fig. 4 is a detail sectional view taken as indicated by the angled arrows IV—IV in Fig. 1 showing one of the bracket components of the sustaining rack provided in the machine for the thread supply packages.

Fig. 5 is a plan view of the parts shown in Fig. 4.

Figs. 6-8 are perspective views of other parts of the machine which will be individually referred to later herein.

Referring first more especially to Figs. 1-3 of these illustrations it will be noted the frame of my improved spinning machine includes two upwardly-tapering column-like end standards 30 and 31, which, adjacent their tops, are rigidly

connected by a pair of vertically-spaced main horizontals 32 and 33 disposed in the central longitudinal plane of the machine, and, which adjacent their bottoms, are similarly connected by a pair of laterally-spaced symmetrically-disposed horizontals 34 and 35 lying in a common transverse plane. At one end of the machine the frame has a relatively low supplementing extension 36 comprising a transverse end member 2 connected to the standards 30 and 31 and of the end member 31 of the frame extension 36, floor irregularities can be compensated for to insure support of the machine in true upright position with absence of sagging at the region of support. In the present instance the frame of the machine also includes two medial standards 43 (see Fig. 1) which extend up to the horizontal 33, and which, like the end standards 30 and 31, are supported by vertically-adjustable elements 44. Serially arranged in closely spaced relation along opposite sides of the machine are spindles 45 for spools S onto which individual multi-filament threads T are wound as they are twisted, said spindles being supported in a manner later on explained, by a fixed rail 46 which extends lengthwise of the machine between the standards 30 and 31 at a level somewhat above the lower frame horizontals 34 and 35. The spindles 45 are rotated through frictional contact with a horizontally-arranged endless belt 47 which passes about flanged pulleys 48 and 49 at opposite ends of the machine. As shown the pulley 49 is affixed to a vertical shaft 50 journaled in bearing brackets 51 and 52 extending outward from the standard 31, and the pulley 48 secured to the shaft of a vertical axis electric motor M which is supported by a carriage 53 with rollers 54 engaged in the hollows of the channel horizontals 38 of the frame extension 36. Attached at one end to the motor carriage 53 is a chain 55 which passes from beneath part way about a sprocket wheel 56 on a transverse shaft 57 suitably journaled in bearings on the frame extension 36, and which has its other end secured to the periphery of said wheel. Affixed to one end of the shaft 57 is an arm 58 from which a weight 59 is suspended with capacity for being adjusted along said arm. Through the drive means just described, the belt 47 is at all times maintained under yielding tension, and it is to be remarked that the parts constituting this means are so arranged as to be entirely within the confines of the framework lengthwise of the machine.

In order that large thread supply packages P as they come from the manufacturer may be

accommodated in the machine out of interfering contact with each other but in axial alignment with the spindles 45, I have provided a rack means of special construction for the description of which reference will be had to Figs. 1, 3, and 4-6 of the drawings. This rack means includes a plurality of brackets 62, each supporting four of the packages P, two of them in transverse relation at a high level and two of them in transverse relation at a lower level offset with respect to the first two in the direction of the length of the machine. Thus collectively the brackets 62 form a rack by which the packages P are supported in close contiguity in staggered relation. As shown in Fig. 6, each bracket 62 comprises a main component 63 and a number of supplemental members 64, 65, 66 and 67. The main component 63 of the bracket 62 is of Z configuration having a lateral offset 63a with an upstanding apertured ear 63b at the top for connection, by means of a screw bolt, to the top horizontal 32 of the machine frame and an apertured foot 63c at the bottom for connection in like manner to the horizontal 33 of said frame. The members 64, 65, 66 and 67 of the bracket are exact counterparts of each other, each being of L-shaped configuration with a stud 68 at the outer end of its horizontal arm for a thread package P. The members 64 and 65 are secured in horizontally-aligned relation to the main component 63 of each bracket by screw bolts passed through apertures in their vertical arms and through registering apertures in the upper vertical segment 63d of said main component. The members 66 and 67 of each bracket 62 are similarly secured by screw bolts passed through apertures in their upright arms and through registering apertures in the lower vertical segment 63e of the main component 63.

During the operation of the machine, the threads T are withdrawn upwardly from transversely aligned pairs of packages P in the upper rows at opposite sides of the machine and passed through tension devices 69 and eyes 70 on the lateral arms of T-shaped guide trees 71 which are secured to the top horizontal 32 of the machine frame, one of such trees being separately illustrated in perspective in Fig. 7. The threads T' are similarly withdrawn upwardly from transversely aligned pairs of packages P' in the lower rows at opposite sides of the machine and passed through tension devices 72 and eyes 73 in the lateral arms of substantially straight guide members 74, such as the one separately illustrated in Fig. 8, which are bolted fast to the top horizontal 32 of the machine frame midway between the guide trees 71.

Twisting of the threads is accomplished in the machine by individual travellers 75 each of which, as is common in machines of this sort, is confined to gyration about the spools or bobbins on which the yarns are wound by virtue of being in slidable engagement with rings 76 supported by a vertically-reciprocating traverse comprehensively designated by the numeral 77. The traverse 77 is formed by vertically-spaced pairs of rods 78 and 79 which extend along opposite sides of the machine and which are connected at intervals by cross members whereof there are three in this instance respectively designated 80, 81 and 82, one adjacent each end of the machine and others at intermediate points. Secured in and pendent from the central bosses of the cross members 80-82 are shafts 86, 87 and 88 which pass through guides 89 on the

spindle rail 46. The shafts 86-88 are provided at their lower ends with enlarged adjustably connected heads 86a-88a which bear upon rollers at the ends of the horizontal arms of bell crank levers 90, 91 and 92 respectively which are fulcrumed on hanger brackets 93, 94 and 95 pendent from the spindle rail 46, and which have their vertical arms coupled by means of horizontal links 96 and 97. Individually associated with the bell crank levers 90, 91 and 92 are counterweights 98, 99 and 100. The means for actuating the traverse 77 includes a heart-shaped cam 102 which is affixed to a transverse shaft 103 with bearing support in a bracket 105 reaching inwardly from the standard 30. Engaging the edge of the cam 102 is a roller 106 at the end of one extremity of a double-armed lever 107, which is fulcrumed at 108 on another drop bracket 109 pendent from the spindle rail 46, the other arm of said lever being coupled, by means of a pitman 110, with the weighted bell crank 92. With this arrangement it will be apparent that as the cam 102 is rotated, vertical reciprocatory movements are imparted to the traverse 77 to effect uniform winding of the twisted threads along the spools S. The combined effect of the weights 98, 99 and 100 is to effectively counterbalance the traverse 77 and the parts connected to and supported thereby, the weight 98 being made somewhat heavier than the others to counteract the influence of the cam lever 107 and pitman 110, the whole system thus favoring high speed operation of the machine.

In order to prevent straining of the traverse actuating mechanism and possible binding of the shafts 86-88 in their guides 89, the pendent brackets 93 and 109 are rigidly tied to each other and to the standard by a horizontal yoke-like bracing means composed as shown in Fig. 1 of separable symmetrically disposed pairs of components 111 and 112.

Each of the traveller rings 76 is supported on an internal peripheral shoulder of an annular holder 115 and held against displacement, with capacity for convenient removal from above.

The feed rolls of the machine by which the threads T are drawn from the individual supply packages P are indicated at 145 in Fig. 1, the same being journaled in shield housings 146a on bracket arms 146 attached to and extending inwardly from a pair of vertical slide rods 147 which pass through guide apertures in the spindle rail 46. Secured to the feed rolls 145 are spur gear wheels 148 which mesh with driving spur gears 149 on shafts 150 and 151 extending longitudinally of opposite sides of the machine and journaled in suitable bearings afforded by the standards 30 and 31. The rolls 145 are rotated in unison but in opposite directions by virtue of being connected by pairs of intermeshing spur gears 152 and 153 respectively at their opposite ends which latter protrude through the standards 30 and 31 (see Fig. 3). Affixed to the shaft 150 beyond its gear wheel 153 at the standard 31 is a spur pinion 154, which, through an idler 155, is driven from a gear wheel 156 on a short horizontal shaft 157 whereof one end is journaled in said standard and whereof the other end is journaled in a bearing on the bracket 51 previously referred to. At its outer end, the shaft 157 carries a worm wheel 158 which meshes with a worm 159 on the vertical shaft 50 also hereinbefore mentioned. Affixed to the shaft 150 beyond its gear wheel 152 at the standard 30 is a pulley 160 which, through an endless belt 161 is

connected to a smaller pulley 162 on the outer end of a short shaft 163 journaled in a suitable bearing at the lower part of said standard. A worm 165 at the inner end of the shaft 163 meshes with a worm wheel 166 affixed to the shaft 103 which carries the traverse actuating cam 102. Through the drive system just described, the rolls 145 at opposite sides of the machine and the traverse 77 thus derive their motion from the transmission shaft 50. Shields 169 secured to the fixed parallel rods 170 extending between the standards 30 and 31 cover the sides of the individual gear couples 148, 149 by which the rolls 145 are driven, as well as the shafts 150 and 151 and in conjunction with shields 146a preclude entanglement of the threads T with said gear couples and shafts. Eyes 171 on the cover shields 146a serve to keep the threads T centralized with respect to the spool spindles 45.

Extending transversely of the intervals between the spool spindles 45 are fly guards 172 of sheet metal or the like that confine the individual threads T and thereby prevent fouling of adjacent threads during the twisting. The fly guards 172 are secured at their bottoms to the individual brackets 136 whereon the spool spindle carrying arms are fulcrumed, and at their tops to the cover shields 169 respectively at opposite sides of the machine, certain of said guards extending with clearance through the longitudinal slots in the transverse members 80—82 of the traverse 77.

En route downwardly from the eyes at the outer ends of the guides 71 and 74 to the rolls 145 at opposite sides of the machine, the threads T pass first over guide rollers 175 which freely and independently revolve about horizontal supporting rods 176 extending between lateral arm projections 177 of the standards 30 and 31 at the level of the frame longitudinal 33; thence over similar guide rollers 178 on parallel rods 179 extending between said standards 30 and 31 at a somewhat lower level; and then through eyes on the vertical rods 147. As shown in Fig. 1 each thread T passes several times about its draft roll 145 before continuing on to the traveller 75 associated with the spool S upon which the finally twisted yarn is collected, the several convolutions of the thread being maintained in spaced relation by a notched comb-like separator 181 mounted above said draft roll.

As seen in Fig. 3, the tensioning devices 69 and 72 are so positioned that the entrant ends of their spirals are centrally above the packages P from which the respective threads are taken. This positioning of the devices 69 and 72 in relation to the packages P and the various thread guides is important to the successful operation of the machine for the purpose set forth.

Having thus described my invention, I claim:

1. An overhead creel for a spinning machine having a straight-line longitudinal row of vertical axis spool spindles spaced with allowance of but small working clearances between them, said creel supporting in upright position a corresponding number of thread supply packages of large diameter as compared to that of the spools, grouped in spaced straight-line longitudinal rows in a common vertical plane, with the packages of one row staggered relative to those of an adjacent row and with a package disposed in the transverse vertical plane of each spindle, and said creel comprising a longitudinally-arranged bar; brackets in transverse relation to the bar each supporting at least one supply package in each of the several rows; and guides overreaching the 75

individual packages to receive the threads overend from the packages and thereafter direct the threads downward to the corresponding spools.

2. An overhead creel for a spinning machine having a straight-line longitudinal row of vertical axis spool spindles spaced with allowance of but small working clearances between them, said creel supporting in upright position a corresponding number of thread supply packages of large diameter as compared to that of the spools grouped in two spaced straight-line longitudinal rows in a common vertical plane, with the packages of one row staggered relative to those of an adjacent row and with a package disposed in the transverse vertical plane of each spindle, and said creel comprising a longitudinally arranged bar; a plurality of brackets each comprising a Z shaped main component and counterpart pairs of L shaped components each with a vertical stud for impalement of a supply package; means for detachably securing the several components to each other and to the aforesaid bar, whereby a package in one row is supported in offset relation to a package in the other row in the direction of the length of the machine; and guides connected to said bar and over-reaching the individual packages to receive the threads over end from the packages and to direct the threads downward to the corresponding spools.

3. The invention according to claim 1, wherein the guide for each thread supply package in the upper row is in the form of a tree upstanding from the longitudinal bar of the creel with a lateral arm at the top having an eye in its outer end; and wherein the guide for the thread of each supply package in the lower row is in the form of an arm extending laterally from said bar and likewise having an eye in its end.

CHARLES CHIPMAN.
